JAMES KIRKLEY, OF CHICAGO, ILLINOIS.

Letters Patent No. 70,862, dated November 12, 1867.

IMPROVED NUT-TAPPING MACHINE.

The Schedule referred to in these Letters Patent and making part of the same.

TO ALL WHOM IT MAY CONCERN:

Be it known that I, JAMES KIRKLEY, of Chicago, in the county of Cook, and State of Illinois, have invented an improved Nut-Tapping Machine; and I do hereby declare that the following is a full, clear, and exact description thereof, reference being had to the accompanying drawings, making a part of this specification, in which—

Figure 1, sheet 1, is a front elevation of my improved tapping machine, adapted for using four taps.

Figure 2, sheet 1, is an elevation of one end of the machine.

Figure 3, sheet 2, is a section taken in the vertical plane indicated by red line $z z$ in fig. 1.

Figure 4, sheet 2, is an enlarged view, in detail, of one of the tap-spindles and its bearings.

Similar letters of reference indicate corresponding parts in the several figures.

This invention relates to a novel mode of constructing machinery for tapping nuts, so that many practical difficulties heretofore found to exist in machines of this class may be obviated.

The main object of the invention is to employ, in conjunction with a gang of taps, which are applied to spindles that rise and fall in planes perpendicular to a stationary table upon which the nuts are held, a novel apparatus for automatically supplying oil to the taps during their operation upon the nuts, and keeping the parts well lubricated without requiring the attention of the attendant; said apparatus consisting of an elevated reservoir for supplying oil to the nuts through feeding-tubes, a drip-pan and strainer for receiving the oil which is unconsumed, and a pumping apparatus which will elevate the oil from the drip-pan and return it to the supply-reservoir, as will be hereinafter described.

Another object of my invention is to provide, in a nut-tapping machine which employs a gang of vertical spindles with a stationary nut-holding table beneath them, a simple and efficient means whereby the pressure of the taps upon the nuts can be adjusted and regulated to a nicety for tapping nuts of different sizes, at the same time providing for enabling the attendant to raise or depress any one of the spindles at pleasure, as will be hereinafter described.

To enable others skilled in the art to understand my invention, I will describe its construction and operation.

In the accompanying drawings, A represents a cast-iron frame, which is adapted for containing and supporting the several parts employed in the operation of tapping nuts. B is the upper horizontal bar, with journal-boxes or bolsters for supporting spur-wheels. C is the lower horizontal bar, having journal-boxes for guiding the tap-carrying spindles, and also bearings for the fulcra of levers, which are used to raise or depress the spindles. D is the operator's table or bed, which is flanged, as shown in cross-section, fig. 3, and also adapted for receiving the removable nut-holders. E is a bracket, applied to frame A for supporting the outer end of the driving-shaft and the cone-pulleys P, which are upon this shaft. F is the upper oil-reservoir, G the lower oil-receiver, and G' is a finely-reticulated strainer, which is applied to the receiver G. H H represent the taps and their shanks; I, removable socket-pieces on the lower ends of the spindles J, for receiving and firmly holding the upper ends of the tap-shanks. The socket-pieces I are made of different sizes, to suit the size of the taps used, and the shanks on all of these socket-pieces are of one given size, so as to fit the sockets which are made in the lower ends of the spindles J, as shown in fig. 4. The spindles J may be made with grooves or slots in them, as shown in fig. 4, at J', with feathers in the hubs of the spur-wheels I; or these spindles may be made with feathers or tenons of suitable length, fitting into corresponding grooves in the hubs of wheels L. By this latter means the operator may raise the spindles, so that the lower parts of the feathers will pass out of the top of the spur-wheel L, and thereby allow the attendant to stop the rotation of any one spindle at pleasure, without stopping all of the spindles. K are collars or bearings on the spindles J, which receive rings J³ between them, to which ring the forked ends of levers R are pivoted. These levers R are connected by vibrating links R' to the bar C, so as to form movable fulcra for allowing the levers to vibrate freely without causing the rings J³ to bind on the collars K, nor the spindles to bind in their bearings. L are spur-wheels with sleeve-journals. These wheels have feathers in their hubs, working in long slots in their respective spindles J, as above stated, by means of which rotary motion is communicated to them from the main shaft O. These wheels L engage with and are operated by pinion-spurs, which form part of the double-gear wheels M. These wheels M consist of bevel-gears and spur-pinions, the former of which engage with bevel-pinions N N on the main driving-shaft.

O. By this arrangement, rotary motion is communicated to all the spindles J simultaneously. Q represent guides for the foot-levers or treadles S, each one of which latter is attached by a rod, T, to its respective forked lever R, for enabling the attendant to raise or depress any one of the spindles at pleasure by means of his foot. Provision is made for attaching weights W to the rear ends of the levers R, as shown in fig. 4, by means of which the downward pressure (weight) of the spindles J, and their taps, can be diminished; as in the case of tapping very light nuts, where the entire weight of the spindle would be too great.

The forcing-pump *a* is used for returning oil to the upper reservoir or cistern F. I do not confine myself to a particular form or location of pump for this purpose, as a pump and the oil-cistern may be so located that, by means of conducting pipes, oil can be supplied automatically to a number of machines in one establishment.

The pipe *b* is used for returning oil to the upper reservoir F. *c* is the overflow pipe, for conducting oil to the lower cistern, in case the upper one becomes too full; *d d* a pipe carrying oil from the upper cistern F to the distributing pipes *e e*. These latter pipes have stop-cocks applied to them, for regulating the flow of oil, and for cutting off the oil from any tap when it is found desirable to do so; *f f* are the upper and lower pulleys, for driving the pump; *g*, a belt connecting these pulleys. On the inner end of the shaft of the lower pulley *f* is a crank, which connects by means of a pitman, *i*, with the plunger-rod of the pump.

The table or bed D is flanged around its edges, for the purpose of preventing the escape of oil therefrom. This table has rectangular apertures through it, for receiving the nut-boxes or nut-holders *h*, as shown in fig. 3, which are made, externally, of uniform size to fit the apertures in the table D. The recesses in the nut-holders are made in sizes suitable for tapping nuts of various sizes and shapes, as many different nut-holders being required as there are different sizes and shapes of nuts to be tapped. The hole which is through the centre of the bottom of each nut-holder should be of a size which is adapted to receive freely through it the instrument used in tapping the nut.

The operation is as follows: Power being applied to the main shaft by means of a driving-belt passing over cone-pulley P, motion is transmitted, by means of bevel-spur wheels N N, to the double-gear wheels M, and thence to the spindles J, all of which latter are rotated in the same direction. Motion from the main shaft O is also imparted to the pump *a* by means of the belt and pulleys above described, so that the oil can be kept constantly flowing from one cistern to another, and through the discharge pipes *e e* upon the taps H, and through the nut-boxes or holders *h*, thereby effecting the most perfect lubrication of the parts requiring oil, without the attention of the operator.

The nuts to be tapped being convenient to the operator, he takes a nut in one hand, places his foot on one of the treadles S, raises the spindle thereof, and drops the nut into the nut-box. He then steps to the next spindle, and repeats the same operation. As soon as his foot is removed from the treadle of the first spindle, the latter falls and at once commences to cut the thread; and by the time the operator has supplied all the nut-boxes with nuts, the tap on the first spindle will have completed its work, so that he returns and again makes a round as before, and this continues until the shanks of the taps are all full of finished nuts. The nuts are removed from the upper ends of the shanks of the taps by detaching them from the socket-pieces I, to do which the motion of the spindles should be stopped by slipping the driving-belt from the cone-pulleys. Should feathers be constructed upon the spindles, as above stated, the motion of the latter can be stopped, and the taps detached by simply raising them to the proper height for disengaging the feathers from the hubs of the wheels L.

In tapping very small nuts, requiring fine threads, weights, W, will be applied to the rear ends of the spindle-levers, and adjusted thereon so as to modify the pressure of the spindles and taps, as may be found necessary.

It will be seen from the above description that the spindles carrying the taps move up and down in vertical planes above the bed which sustains the nut-boxes, and that the taps are made to pass through the nuts, while the nuts remain stationary. This enables the operator to convey the oil to the exact points required, the streams flowing constantly down through the grooves in the taps, and effectually lubricating the parts as the nuts are being cut, without any labor or attention whatever on the part of the operator.

By the arrangement shown and described, the weight of the spindles, in all cases, is sufficient to cause the taps to enter the nuts, and commence cutting immediately the nuts are dropped into their boxes, and the taps allowed to fall upon them.

Having described my invention, what I claim as new, and desire to secure by Letters Patent, is—

1. The arrangement of a gang of die-boxes, a gang of taps, a gang of rotating and vertically sliding spindles, in the relation shown to gears, and a shaft, O, the parts above named being constructed and operated substantially as herein described.

2. The arrangements of the oil-receiver G, oil-supply reservoir F, pipes *d e*, and forcing-pump *a*, in combination with the die-bed and vertically sliding and rotating spindle, carrying taps, substantially in the manner and for the purpose herein described.

3. The combination, with the nut-tapping machine, constructed and operating substantially as herein described, of an automatic lubricating and oil-elevating apparatus, constructed and operating substantially as herein described.

4. The arrangement of the levers R, weight W, links R', treadles S, and vertically-sliding and horizontally-rotating spindles, carrying taps H, in relation to one another and to the die-bed D, substantially in the manner and for the purpose described.

JAMES KIRKLEY.
